UNITED STATES PATENT OFFICE.

DAVID E. GOGGIN, OF NEW YORK, N. Y.

VARNISH FIRE

Application filed January 24, 1927. Serial No. 162,955.

This invention relates to apparatus used by varnish makers to heat varnish kettles, and generally known to the trade as fires. It is the practice in the making of varnish to subject such varnish to a prolonged boiling and refining process. This process is carried out in relatively large wheeled kettles which are adapted to be moved into and out of cooperation with a suitable heating apparatus, the heat from which is imparted to the kettle for the purpose of boiling the varnish therein.

Originally these fires consisted in an ordinary coke or charcoal fire beneath the varnish kettle. More recently, oil and gas have been used as a source of heat. The oil or gas is burned in the form of a flame and these flames, which find their origin in a pit beneath the kettle lap upwardly out of the top 20 of the pit and impinge the bottom of the kettle.

In the boiling of varnish, heavy highly combustible fumes are given off. These fumes and vapor overflow the top of the kettle and descend along the sides thereof. When such combustible fumes come into contact with an open flame, a fire is apt to result and such fires are common in varnish works.

It has long been recognized that an open flame around a varnish kettle was dangerous and varnish manufacturers have invariably been constructed, so that in the event of such fire, which not infrequently occurs, no serious damage would be done, other than the spoiling of the bath of varnish contiguous to which the fire occurred.

All of the foregoing facts have been recognized in the art. There has never, heretofore, been a construction suggested or conceived which will economically effect the heating of varnish kettles without an incident open flame. True, grids and perforated plates have been placed over the fire and beneath the kettle, but my experience has shown that these grids and plates do not hold back the flame, which, to effect complete combustion generally burn above said grids or plates.

In the present invention, I have departed from the prior practice and instead of depending upon an open flame to heat the kettle, I employ, in contradistinction, radiant heat, evolved from a heating element of highly refractory material adapted, in turn, to be heated by the impingement of flames

thereon. In other words, the fire of this invention embodies a refractory heating element against which a flame is directed to heat the element to a relatively high temperature, generally to a white heat, and this element becomes a substantially incandescent heating element from which the heat to boil the varnish is derived. By thus heating the kettle, I eliminate the presence of an open flame and render the construction much safer than heretofore.

In practically carrying out the invention, the construction preferably embodies a substantially cylindrical pit, positioned below the floor level. Extending radially from one side of the pit and near the bottom thereof is a flame passage through which the flame, propagated from any suitable source, e. g., a gas or oil injector, is forced into the pit. Supported coaxially of the pit and near the upper edge thereof is a slab or plate of refractory material. In practice, this slab may be conveniently supported on refractory piers from the bottom of the pit. The slab is positioned slightly below the top of the pit and is of somewhat less diameter than the diameter of the pit. Directly above and below the slab, inwardly extending annular flanges are formed and these flanges are of sufficient width to extend well in over and under the slab in spaced relation to the upper and lower faces of the slab. As a result of this construction, flame entering the pit through the flame passage swirls about in the base of the pit and is directed upwardly against the bottom of the slab, the lower flange serving as a baffle to insure that the flame impinges on the slab and does not pass about the outer edge of said slab.

To further preclude the passage of the flame around the margin of the slab and out through the top of the pit, the upper flange is provided and said upper and lower flanges co-operate with the slab to provide such a circuitous passage for the flame that combustion is completed within the pit and no flames exit from the top thereof. By directing the flame against the slab of refractory material, it is caused to attain high temperature and gives off its radiant heat in an upward direction and through the top of the pit to impinge directly upon the varnish kettle positioned directly above said pit.

The structure is simple and economical to manufacture and furthermore is readily accessible in the event that repairs are neces-

sary, so that in such event, the repairman is not required to disrupt masonry in order to make the necessary repairs or to clear out the device.

5 Features of the invention, other than those referred to, will be apparent from the hereinafter detailed description and claims, when read in conjunction with the accompanying drawings.

10 The accompanying drawings illustrate one practical embodiment of the invention, but the construction therein shown, is to be understood as illustrative, only, and not as defining the limits of the invention.

15 Figure 1 is a perspective view showing the fire of this invention, certain parts being shown in section in the interest of clearness; and,

20 Figure 2 is a longitudinal vertical section through the construction of Figure 1.

In the drawings, 1 designates the pit, which may be of any suitable contour, but is preferably circular as shown. Near its base is a radially outwardly extending flame 25 passage 2 provided at its end with an opening 3 with which an oil or gas injector 4 is associated. The pit is set into the ground or floor of the treating room of the varnish works and is built in permanently. 5 designates the floor level.

30 The pit and flame passage are constructed from highly refractory material. Firebrick may be used for this purpose, but I preferably employ slabs of carborundum and preferably provide the sides of the pit and passage, as well as the top wall of the passage with suitable heat insulation 6, as shown.

35 Positioned within the pit is a slab 7. This slab is circular and is of refractory material, preferably carborundum. It is of slightly less diameter than the diameter of the pit, and is supported on a plurality of piers 8 in a position slightly below the floor level 5. The piers 8 may to advantage be also of carborundum. Directly above and below the slab 7, and in spaced relation thereto, flanges 9 and 10 extend in an inward radial direction from the side wall of the pit. These flanges are sufficiently wide to appreciably 45 overlap the outer margin of the slab, so as to form a circuitous passage from the base of the pit about the inner edges of the flanges and the outer periphery of the slab to the open top of the pit. The purpose of the flanges 9 and 10 is to provide this circuitous 50 passage and to serve as baffles to preclude the exit of flame from the top of the pit and to force said flame to impinge upon the slab 7.

55 When the burner or injector 4 is functioning, a flame is projected through the flame passage 2 into the base of the pit, where it swirls about and upwardly to directly impinge upon the under side of the slab 7, as shown by the arrows in Figure 2. Sufficient 60 air is allowed to enter through the opening 3

65 by means of the injector or injector action, or otherwise, to accomplish complete combustion of the fuel, so that by the time the flame has impinged the slab 7 and been directed downwardly against the flange 10, and laterally against the side wall of the pit of said flange, combustion will be complete. It therefore follows that no flame will pass through the open top of the pit for if the flame is not entirely spent by the time it 70 strikes the side wall of the pit, it will again be deflected by the flange 9.

75 My experience has shown that a structure such as described will so function as to cause the slab 7 to assume a substantially incandescent state while no flame exits through the open top of the pit. The intense heat absorbed by the slab is given off, in the form of radiant heat, in an upward direction and passes out through the open top of the pit 80 to directly impinge upon the varnish kettle 85 which is positioned above the pit.

85 It therefore follows that there is no open flame incident to the operation of the fire of this invention, and the waste products of combustion passing through the open top of the pit will efficiently and effectually keep vapors or fumes which overflow from the kettle from entering the pit and igniting 90 therein.

95 The structure of this invention is absolutely safe and constitutes a pronounced step in advance over prior devices used in the boiling of varnish.

100 The air to support combustion may be fed to the injector or burner 4 in any suitable manner. I find it highly economical, however, to feed heated air to the burner or injector in order that the air fed thereto will not tend to cool off the structure after passing 105 into the same. It is highly practical and economical to employ the heat deflected by the flame to preheat the air prior to feeding it to the injector. Thus, in Figure 2, I have shown a coil of pipe 12 embedded in the insulation 6 about the flame passage and pit. Air is fed into the free end of the pipe, preferably under pressure, and is circulated about through the pipe 12 and becomes highly heated before it is fed to the injector 4. The air duct is shown in the form of a pipe, but it is within the purview of this invention to interpose a layer of firebrick or other refractory material between the insulation and the lining of the apparatus, and to form within 110 this firebrick a duct through which air may be fed in substantially the same manner as I have referred to. It is found, in practice, that the heat generated within the flame chamber and pit is so intense as to efficiently and economically heat the air in the manner described.

115 The structure of this invention is particularly intended for use in the manufacture of varnish. I am aware, however, that the 120

structure described and claimed may be used to advantage in the boiling of oils, resins, gums, etc., used in industries other than the varnish industry and I do not therefore restrict the invention to the particular use hereinbefore specified.

The foregoing detailed description sets forth the invention in its preferred practical form, but the invention is to be understood as commensurate with the appended claims.

Having thus fully described the invention, what I claim as new and desire to secure by Letters Patent is:

1. A varnish treating fire embodying an imperforate slab of refractory material, and means for directing a flame against said slab and entirely around the same for the purpose of heating the same to a substantially incandescent state, whereby the slab is adapted to radiate radiant heat for the purpose of heating a varnish kettle.

2. A varnish treating fire embodying a pit, a slab of refractory material positioned adjacent but below the top thereof and entirely out of contact with the walls of said pit, means for producing a flame within the pit below the slab, and baffles extending inwardly from the side of the pit to preclude the passage of the flame upwardly about the outer periphery of the slab and to cause said flame to impinge the lower face of said slab for the purpose of heating the same, whereby said slab is adapted to radiate heat thus imparted to it to a varnish kettle positioned above the pit.

3. A varnish treating fire embodying a pit, a slab of refractory material positioned adjacent but below the top thereof and entirely out of contact with the walls of said pit, means for supporting said slab from the bottom of the pit, means for producing a flame within the pit below the slab, and baffles extending inwardly from the side of the pit to preclude the passage of the flame upwardly about the outer periphery of the slab and to cause said flame to impinge the lower face of said slab for the purpose of heating the same, whereby said slab is adapted to radiate heat thus imparted to it to a varnish kettle positioned above the pit.

4. A varnish treating fire embodying a pit, a slab of refractory material positioned adjacent but below the top thereof, a plurality of refractory pillars bearing on the bottom of the pit and supporting said slab in the desired position, means for producing a flame within the pit below the slab, and baffles extending inwardly from the side of the pit to preclude the passage of the flame upwardly about the outer periphery of the slab and to cause said flame to impinge the lower face of said slab for the purpose of heating the same, whereby said slab is adapted to radiate heat thus imparted to it to a varnish kettle positioned above the pit.

5. In a fire for treating varnish, a pit of refractory material provided near its base with a laterally extending flame passage of refractory material, means associated with the flame passage for directing a flame through the passage into the pit, a slab of refractory material supported in and positioned below the top of the pit and above the flame passage and entirely out of contact with the walls of said pit, and refractory flanges extending inwardly from the sides of the pit in spaced relation thereto, and above and below the slab, and respectively overlying and underlying the margins of said slab to provide with the slab a circuitous passage from the bottom to the top of the pit, whereby flame from the flame passage is required to impinge the slab for the purpose of heating the same.

6. In a fire for treating varnish, a substantially circular pit of refractory material provided near its base with an outwardly radially extending flame passage of refractory material, means associated with said passage for directing the flame through the passage and into the pit, a circular slab of refractory material positioned below the top of the pit and above the top of the flame passage in coaxial relation with said pit and spaced from the side walls of the pit, means for supporting said slab in position, and annular flanges of refractory material extending inwardly from the side wall of the pit in spaced relation to and above and below the slab and overlying and underlying, respectively, the outer periphery of the slab.

7. In a fire for treating varnish, a substantially circular pit of refractory material provided near its base with an outwardly radially extending flame passage of refractory material, means associated with said passage for directing the flame through the passage and into the pit, a circular slab of refractory material positioned below the top of the pit and above the top of the flame passage in coaxial relation with said pit and spaced from the side walls of the pit, pillars extending upwardly from the bottom of the pit and supporting said slab in position, and annular flanges of refractory material extending inwardly from the side wall of the pit in spaced relation to and above and below the slab and overlying and underlying, respectively, the outer periphery of the slab.

8. In a fire for treating varnish, a substantially circular pit of refractory material provided near its base with an outwardly radially extending flame passage of refractory material, means associated with said passage for directing the flame through the passage and into the pit, a circular slab of refractory material positioned below the top of the pit and above the top of the flame passage in coaxial relation with said pit and spaced from the side walls of the pit, pillars

extending upwardly from the bottom of the pit and supporting said slab in position, annular flanges of refractory material extending inwardly from the side wall of the pit in spaced relation to and above and below the slab and overlying and underlying, respectively, the outer periphery of the slab, and

insulation positioned exteriorly of the side walls of the pit and flame passage and the top wall of the flame passage.

In testimony whereof I have signed the foregoing specification.

DAVID E. GOGGIN.
